[57] **CLAIM**

The ornamental design for fly tying bench, as shown and described.

DESCRIPTION

FIG. 1 is a perspective view of the fly tying bench showing my new design;

FIG. 2 is a left side elevational view, the right side being a mirror image thereto;

FIG. 3 is a front elevational view thereof; and

FIG. 4 is a top plan view thereof.

The bottom and rear views of the fly tying bench are substantially flat and unornamented.

*Fig. 1.**Fig. 2.*
